MOTOR-SEATING CARRIAGE FOR PORTABLE ELECTRIC MACHINES

Filed May 9, 1939

Inventor,
Frederick Toop.

By Sterling P. Buck,
Attorney.

UNITED STATES PATENT OFFICE

2,204,110

MOTOR-SEATING CARRIAGE FOR PORTABLE ELECTRIC MACHINES

Frederick Toop, York, Pa., assignor to Petco, Inc.,
York, Pa., a corporation of Delaware

Application May 9, 1939, Serial No. 272,583

7 Claims. (Cl. 280—61)

This invention relates to bearings and guides in the general class of machine elements, and especially to a wheeled vehicle or bearing support to which I give the title Motor-seating carriage for a portable electric machine.

One object of the invention is to provide a carriage or truck whose upper surface is concaved in the specific manner described herein-after so as to conform to the lower side of an electric motor casing of the shape shown in my patent application No. 212,807, so such motor casing fits snugly into the concavities of the carriage and is thereby prevented from being moved forward or rearward or laterally or rotatively with respect to the carriage; but is movable in all directions with the carriage, and can be lifted from the carriage without any preliminary act other than manipulating a simple spring-pressed lever or latch.

A further object of the invention is to provide the rear and lateral parts of the carriage with casters to support it on a table top or other surface and enable it to be rolled in straight lines and in circuitous lines while holding the motor casing axially parallel to the supporting surface, viz., in such relation that the transmission shaft, or tool-carrying shaft that extends from the motor-casing, is horizontal or axially parallel with the surface on which the carriage is mounted to travel towards and from the material to be worked upon; whether said material be on or adjacent to said supporting surface; or whether said material be sheet metal to be sheared or trimmed; or whether the material is to be bored or reamed or sawed or ground or hammered.

Another object of the invention is to provide a carriage of this kind with upstanding flanges in the proper position as to be respectively against forwardly facing and rearwardly facing surfaces of said motor casing so as to provide a very simple and effective means for cooperating with the latch in preventing forward and rearward movements of the motor casing on said carriage while being cooperative with said latch and with an upwardly curved rear part of the carriage for preventing lateral movement of the motor casing with relation to the carriage.

Another object is to provide a carriage of this kind that is very rigid and strong, consistent with comparative lightness, and which is composed of few and simple parts so as to be produced and used at the minimum of expense.

Other objects and important features are pointed out or implied in the following details of

description, in connection with the accompanying drawing in which:

Fig. 1 is a top plan view of my motor-seating carriage, in full lines, and of a motor casing seated thereon, as indicated in broken lines, viz., dot-dash lines, the dotted lines indicating hidden parts that are shown in the other views.

Fig. 2 is a longitudinal vertical sectional view of the carriage, the motor-casing not here being shown.

Fig. 3 is a front end view of the carriage in full lines and in dotted lines, and of the motor casing in dot-dash lines.

Fig. 4 is a view partly in front elevation and partly in vertical cross-section, showing the socketed front portion of the motor-casing to be seated on this carriage and secured thereon by the socket and slide-bolt in cooperation with a tangentially grooved stud on an upright at the front of the carriage.

Referring to the drawing in detail, in which, similar reference numerals refer to similar parts in the several views, the invention is described in detail as follows:

The main unit of the carriage is quite rigid, being preferably of cast steel or other strong metal; and it comprises a normally horizontal beam 5 having an upturned or upwardly curved rear end portion whose surface 6 is laterally concaved so as to conform to the convexed lower-rear end portion of the motor casing C. It also comprises two laterally projecting arms 7 and 8 each being united with the front end portion of the beam 5 and being curved upward from the latter so as to provide concave seating surfaces 9 and 10 of proper curvatures to conform to front-lower convex portions of the motor casing C.

The motor-casing C comprises two cylindrical parts C1 and C2 in offset relation to one another and having, respectively, a forwardly facing surface C3 and a rearwardly facing surface C4 at opposite sides of an elliptical section C5 which latter, when seated in the adjoining concave seats 9 and 10, being non-cylindrical, will not be rotated by torque of the tool-driving shaft or spindle S while the combined weight of the motor-casing and its engagement with the slide-bolt or latch B effectually counteract the torque. The slide-bolt B, which is normally seated in the tangential groove 15 of the cylindrical stud or keeper 16, would limit the turning movement of the motor practically to zero with respect to the carriage, even if the torque would cause such turning movement to start. The tangentially grooved

stud 16 projects rearwardly from an upright element 17 with which it is united and which is united with the front part of the arm 8; and this stud normally fits snugly but easily in a 5 socket C6 (Fig. 4) of the motor-casing. A bore C7 in the motor-casing has the slide-bolt B therein and yieldingly held in its latching position by a compression spring C8; but when the slide-bolt is pressed inward against the spring-pressure, 10 the socket C6 is then unobstructed so the cylindrical stud 16 can be caused to enter therein by moving the motor-casing forward while in the position of Fig. 4; and when the motor-casing is arrested by its contact with the upright 17, and 15 is then turned down into the substantially concave seat of the carriage, to the position shown in Fig. 1 (in dot-dash lines), the spring C8 then pushes the slide-bolt B into the tangential groove 15, thereby securely latching the motor-casing to the carriage.

The upturned surfaces 9 and 10 also help to prevent the motor-casing from moving laterally with respect to the carriage. An upstanding flange 11 is united with the rear edge of the arm 25 7 and normally rests against the rear upright surface C4 for aiding in preventing the motor-casing from moving rearward and sliding up the concave 6. An upstanding flange 12 is united with the front edge of the arm 8 and normally 30 rests against the front upright surface C3 for aiding in preventing the motor-casing from moving forward with respect to the carriage. At this point, it should be understood that the main purpose of the flanges 11 and 12 is to relieve 35 the slide-bolt from being battered and worn by repeated forward and rearward movements in the rough usage to which a device of this kind is likely to be subjected, for instance, when an operating tool is connected to the rotary tool-connector thru the medium of a flexible shaft by which the carriage and motor-casing are pulled and pushed about on the floor of a factory, shop or garage.

When the user desires to use the electric motor-tool independently of the carriage, he can do so 45 without any preliminary action other than grasping the motor-casing or its handle, turning it through 90 degrees to the position shown in Fig. 4, pressing the slide-bolt B inward, and pulling 50 the motor-casing rearward from engagement with the cylindrical stud 16; and, inversely, when the user desires to use the motor-tool in conjunction with the carriage, he merely causes the 55 stud 16 to enter the socket C6 while holding the slide-bolt B depressed, then turns the motor-casing from the position of Fig. 4 to that of Fig. 1 (in dot-dash lines) and releases the slide-bolt so its spring C8 pushes the slide-bolt into the tangential groove 15 and thus secures the 60 casing to the carriage. The carriage may be rolled on its castors 13 in any desired direction in the plane parallel to the surface on which the castor-wheels are seated for traveling movement thereon. These castors, as shown in the 65 drawing, are pivoted in bearings 14 in the respective outer end portions of the arms 7 and 8 and rear part of the beam 5.

Though castors are convenient and comparatively low-cost for providing wheels for this carriage, the invention is not limited to this form 70 of wheels nor to this manner of connecting wheels to the carriage-frame; though the castors are of considerable advantage where quick and easy lateral movements are desired.

My invention is not limited to the exact details of construction and arrangement of elements described in the foregoing, nor as shown in the drawing, for numerous changes may be made within the scope of the inventive ideas as implied and claimed. 5

What I claim as my invention is:

1. In a motor-seating carriage, a rigid unit that is inclusive of a normally horizontal beam which has an upwardly curved rear end portion 10 whose upper surface is laterally concaved and provides a snug seat for the convex rear lower portion of a motor casing of the kind shown, said unit also being inclusive of arms that project respectively rightward and leftward from the 15 front end portion of said beam and are curved upwardly to provide concave seats for the axially offset arcuate or convex surfaces of the front end portion of said motor casing, and supporting wheels operatively connected to the respective outer end portions of said arms in a proper relation to enable the carriage to be rolled forward and rearward with the motor casing snugly seated thereon for purposes specified.

2. The structure defined by claim 1, said wheels 25 being elements of castors that are pivotally connected to said arms so that the carriage can be rolled laterally as well as forward and rearward.

3. The structure defined by claim 1, and a 30 castor operatively connected to said rear end portion of the beam so as to cooperate with said wheels and rigid unit in supporting said motor casing in the axially parallel relation to a surface on which the carriage may be supported for rolling along straight and circuitous lines for purposes specified. 35

4. The structure defined by claim 1, one of 40 said arms having an upstanding flange at its front edge to fit against a forwardly facing surface of said motor casing and thus prevent forward movement of the casing with respect to the carriage, the other one of said arms having an upstanding flange at its rear edge to fit against a rearwardly facing surface of said motor casing and thereby cooperate with said curved upper surface in preventing rearward movement of said 45 motor casing with respect to said carriage.

5. The structure defined by claim 1, said motor 50 casing being snugly seated and fitted on said carriage in the proper relation to prevent forward and rearward and lateral and rotary movements of the motor casing with respect to said carriage and to permit said motor casing to be lifted from said carriage without hindrance or preliminary action other than grasping the motor casing. 55

6. The structure defined by claim 1, in combination with said motor-casing, and means to secure the motor casing against accidental displacement from said carriage, said means being provided with a manipulative element for releasing 60 the motor-casing from the carriage.

7. The structure defined by claim 1, in combination with a motor casing which has a socket 65 therein and a spring-pressed slide-bolt across said socket, said carriage having thereon a stud that is adapted to fit in said socket and is formed with a groove for receiving said slide-bolt so as to cooperate with the latter for securing said motor casing on said carriage and permitting it to be released from the carriage by manipulation 70 of said slide-bolt.

FREDERICK TOOP.
